(57) CLAIM

The ornamental design for a box with strap, as shown and described.

DESCRIPTION

FIG. 1 is a perspective view of a box with strap embodying my new design;

FIG. 2 is a front elevation view thereof of FIG. 1;

FIG. 3 is a rear elevation view thereof of FIG. 1;

FIG. 4 is a left side elevation view thereof of FIG. 1;

FIG. 5 is a right side elevation view thereof of FIG. 1;

FIG. 6 is a top plan view thereof of FIG. 1; and,

FIG. 7 is a bottom plan view thereof of FIG. 1.

In the drawings, the broken lines depict environmental subject matter only and form no part of the claimed design.
